MEASURED SERVICE TELEPHONE SYSTEM

Erich Feist, Berlin-Charlottenberg, and Rudolf Nebelung, Berlin-Siemensstadt, Germany, assignors to Siemens & Halske Aktiengesellschaft, Wernerwerk, Siemensstadt, near Berlin, Germany

Application May 25, 1936, Serial No. 81,624
In Germany June 13, 1935

17 Claims. (Cl. 179—7.1)

The present invention relates to a circuit arrangement for remote communication systems and more especially for telephone systems in which the necessary statements for the computation of fees are indicated on registering devices (printing or stamping devices).

The invention aims at making the construction of the registration devices as simple as possible and simplifying the switching operations necessary for registration. In particular it possesses the advantage that it is applicable in cases where a definite number of fee impulses whose number corresponds to the number of fee units to be reckoned, is transmitted by a device determining the amount of the fee to be charged for a call.

The arrangement according to the invention can thus be applied in systems already in use which involve the transmission of an impulse train consisting of one or more impulses for the purpose of influencing the subscribers' meters in the exchange, without substantially altering the connecting devices, the subscribers' meters being omitted.

The invention consists in that after influencing the registering devices in a manner characterizing the calling line, a characteristic identifying the calling line is registered a number of times corresponding to the number of fee units contained in the amount to be charged for the call.

An embodiment of the invention is represented in the drawings. Of these, Fig. 1 is a circuit diagram showing a subscriber's station, switching equipment for extending calls therefrom, and a pair of registering devices for recording the fees to be charged for calls. Fig. 2 represents one form of registering device which is adapted to perforate a moving tape to record fees.

In order to make the diagram clearer only those switching devices which are necessary for understanding the invention are shown. The switching operations according to the arrangement shown in Fig. 1 are as follows:

It will be assumed that a plurality of subscribers, for example, one hundred subscribers, are associated in the exchange with two registering devices ZZ1 and ZZ2 serving to denote the fees. The subscriber TN sets up a call in the known way over the preselector VW, the first group selector 1GW and additional connecting devices and lines (not shown). After removing the receiver at the calling station TN the call relay R, of which only the contact 4r is shown, energizes. This switches on the rotary magnet (not shown) of the preselector which in the known manner seeks out a first group selector. When such a group selector has been found the following testing circuit is established: earth, battery, wiper d of the preselector VW, contact 4r,

windings II and I of relay T, wiper c of the preselector, resistance W13 in the group selector, contact 4a and 6k, windings II of relays A and B and earth. In this circuit relay T energizes in the preselector and relays A and B in the first group selector. Relay T at contacts 1t and 2t switches the speaking lead through, brings the preselector to rest (by means not shown) and by closing contact 3t guards the free group selector against further seizure. A circuit is established over the subscriber's loop in which relays A and B are maintained energized over their windings I. This circuit runs as follows: earth, winding I of relay B, wiper b of the preselector, contact 2t, subscriber's loop, contact 1t, wiper a of the preselector, winding I of relay A, battery and earth. By the opening of contact 4a a short circuit over relay C previously existing is removed so that this relay can energize over resistance W13, winding of relay C, contact 6k, windings II of relays A and B and earth. Relay C closes its contact 5c and establishes a locking circuit for itself which is maintained throughout the whole duration of the call. In addition it opens contact 13c.

The subscriber now commences to dial. After the first vertical step of the first group selector the off-normal contact 6k is opened, thus disconnecting the windings II of relays A and B. When the first group selector, after hunting in the level to which it has been set, finds a further connecting device the following testing circuit is established: earth, contacts not shown, windings II and I of relay P, wiper c of the group selector and battery potential in the subsequently arranged free connecting device. Relay P by closing its contact 10p guards the free connecting device which has been found against further seizure and effects the other known switching operations which are not represented such as the switching through of the speaking leads, bringing the first group selector to rest, etc. It will be assumed that the repeater for time-zone-metering is arranged after the first group selector. This possesses switching devices which establish the desired traffic direction and the duration of the call in the known manner. By means of further switching devices a metering impulse train which contains a number of metering impulses corresponding to the zone and to the time taken is transmitted over the speaking leads to the final selector LGW at the end of the call.

When after terminating the call the calling subscriber replaces his receiver relays A and B deenergize. By the closing of contact 4a relay C is short circuited so that this relay deenergizes after a short time. The following circuit is then set up: earth, battery, windings II and I of relay Y, contacts 13c and 12p, resistance W14, winding of relay AN and earth.

In this circuit relay AN energizes. Relay Y

energizes after one of the selector switches associated with the registering devices is operated in connection with the calling line. The relay Y energizing in the above-mentioned circuit 5 closes its contact 7y and thereby connects the third winding of relay P to the other speaking lead to which earth potential is applied in the subsequently arranged time-zone equipment so that relay P, whose winding I is short-circuited 10 by the closing of contact 11y, is prevented from a premature release. By means of the battery potential applied to the upper speaking lead through contact 7y the subsequent time-zone equipment is caused to transmit metering impulses whose number depends upon the value 15 and the time of the call. The metering impulses are transmitted to the lower speaking lead and by way of wiper b of the first group selector pass to relay ZR to which earth potential is 20 applied over contact 9y. Relay ZR is caused to energize and deenergize in rhythm with the metering impulses transmitted. Contact 82r is thus opened and closed a number of times. Since, however, the contact closing are of only a short 25 duration winding III of relay P does not de-energize. Only when relay ZR is energized for a protracted period at the end of the transmission of metering current and a short circuit is permanently established over winding III of relay 30 P by contact 82r does this relay release.

By the closing of contacts 16an and 17an the following circuits were established for relays F1 and F2, earth contacts 16an and 15d1, winding of relay F1, battery and earth, and earth, contacts 35 17an and 18d2, winding of relay F2, battery and earth. Relay F1 closes the following circuit for the rotary magnet D1 of the selector WD1 cooperating with the registering device ZZ1: earth, battery, magnet D1, contacts 33f1 and 34p1, and 40 earth, while during the closing of contact 36f2 the following circuit is closed for the rotary magnet D2 of the selector WD2 cooperating with the registering device ZZ2: earth, battery, rotary magnet D2, contacts 36f2 and 37p2, and earth. 45 The rotary magnet D1 advances the wiper a1 and b1 of the selector WD1 and the rotary magnet D2 advances wipers a2 and b2 of the selector WD2 by one step. Through the opening of the magnet contacts 15d1 and 18d2 the circuits set 50 out above for relays F1 and F2 are broken and thus by the opening of contacts 33f1 and 36f2 the above-mentioned circuit for the rotary magnets D1 and D2 are opened. This has the result that the contact 15d1 and 18d2 are again closed 55 and relays F1 and F2 are again operated. Thus the wipers a1, b1 and a2, b2 are advanced once more. This alternate play continues until one of the selectors has reached the contact which is connected to the wiper e of the preselector VW, 60 of the calling subscriber TN. It will be assumed that the selector WD1 cooperating with the registering device ZZ1 is the first to reach the pre-selector of the calling subscriber. The following circuit is then established: earth, windings II and I of relay P1, relay Z1, wiper a1 of selector 65 WD1, wiper e of the preselector VW, contacts 12p, and 13c, windings I and II of relay Y, battery and earth. In this circuit relays Y and P1 energize but not relay Z1. The relay AN arranged 70 in parallel with relay P1 releases. The testing relay P1 of selector WD1 closes its contact 22p1 and thus completes a short-circuit for the high-resistance winding II of relay P1 so that the selector WD2 can no longer be set on the calling subscriber. Furthermore relay P1 closes its con-

tact 28p1 and thereby prepares a short-circuit for winding I of relay U1. By opening contact 34p1 any further influencing of the magnet D1 of selector WD1 and thus any consequent advancement is prevented.

If the case should occur in which the selector WD2 reaches the calling subscriber simultaneously with the selector WD1 the following circuit is closed for the relay AB associated with selector WD2: earth, contact 26p1, wiper b1 of selector 10 WD1, wiper b2 of selector WD2, contact 35p2, winding of relay AB, battery and earth. Relay AB opens its contact 38ab and thereby disconnects the testing relay P2 of selector WD2. In this case therefore, only the registering device 15 ZZ1 is held in readiness.

It will be assumed that the calling subscriber has set up a highly-rated call for which several metering units have to be taken into account. As described above after the setting of the selector WD1 connecting up the exchange meter 20 ZZ1, on the calling subscriber, a circuit was set up in which relay P1 was energized. Relay Z1 which occurs in the same circuit still remains in the normal condition. Only when contact 25 142r is closed, i. e., when the first metering impulse has operated on the relay ZR does an increase in current take place in the above-mentioned circuit by the short circuiting of the high resistance winding I of relay Y. This increase in current causes relay Z1 to energize. If contact 142r is then again opened, relay Z1 again releases. This results therefore, in the 30 metering impulses being transmitted to the first group selector from the time-zone equipment. By the closing of contact 21z1 the following circuit is completed for the printing or stamping magnet SM: earth, contact 21z1, magnet SM, battery and earth. The magnet energizes and 35 stamps or prints on a movable paper strip a characteristic from which the number of the calling subscriber can be recognized (the details of this operation will be described later when describing the arrangement shown in Fig. 2). By the closing of contact 21z1 the following circuit is completed for relay U1: earth, contact 29z1, windings I and II of relay U1, battery and earth. Relay U1 closes its contact 27u1 and this closes 40 a short circuit for its winding I which was prepared at contact 28p1. The relay U1 is thus 45 made slow to act so that during the transmission of the rapid succession of metering impulses the relay does not deenergize. If after the termination of the first metering impulse relay Z1 falls back, the advancing magnet FM which after 50 each metering impulse causes the paper strip to be advanced by a definite amount, is energized in the following circuit: earth, contact 19z1, 20u1, magnet FM, battery and earth. In addition the following circuit is established for relay 55 V1: earth, contacts 39z1 and 31u1, windings I and II of relay V1, battery and earth. Relay V1 closes its contacts 32v1 and thus completes a short 60 circuit for its winding I. This relay is therefore made slow in operation so that this relay also does not deenergize during the transmission of the metering impulses and the repeated opening of contact 30z1. When the second metering impulse becomes operative the stamping or 65 printing of the indication on the paper strip again takes place by the closing of contact 21z1. Furthermore, on the second energizing of relay Z1 the following circuit is established for the zone characterizing magnet ZO: earth, contacts 23z1, 24u1, 25v1, magnet ZO, battery, earth. The 70

5 magnet ZO possesses two operating pins of which one is displaced one step behind the other so that it provides the first characteristic of the calling subscriber which was printed or stamped 10 on the paper strip with an additional zone indication (to be described in more detail in connection with the description of Fig. 2). After the release of relay Z1, that is after the termination 15 of the second metering impulse, the paper strip is advanced again by the operation of magnet FM. Accordingly if, for example, five metering impulses are transmitted, the characteristic for the calling subscriber is represented five times on the paper strip with an additional characteristic 20 whereby the call may be recognized as a zone call. As may be seen the zone magnet is only energized when several metering impulses are transmitted. If, for example, in the case of a local call, only a single metering impulse is transmitted the magnet ZO is not operated and thus the additional indication does not take place.

When the last metering impulse is transmitted 25 the relay ZR in the first group selector remains energized for a protracted period. On account of the continued closing of contact 82r relay P is caused to deenergize. This is the characteristic for the release of the connecting devices which have been taken into use. Since these are known 30 operations which have no bearing on the present invention, they need not be described further.

If the selector WD2 cooperating with the exchange meter ZZ2 is the first to reach the calling subscriber the testing relay P2 of the selector 35 WD2 would energize before the testing relay P1 of selector WD1 and would energize over wiper a2, contact 38ab, relay Z2 (which however does not immediately energize), windings I and II of relay P and earth. By opening contact 37p2, relay P2 brings the selector WD2 to rest and prevents at contact 39p2 the selector WD1 from reaching the calling subscriber. Since when the circuit described above is established the relay AN which is arranged in parallel with relay P2 deenergizes, no further advance of selector WD1 45 is possible.

The registration on the exchange meter ZZ2 takes place in the same manner as in the case of the exchange meter ZZ1. The exchange meter 50 ZZ2 is therefore only partly indicated. The auxiliary devices necessary for its operation correspond to those shown for the exchange meter ZZ1.

For characterizing the calling subscriber a disc 55 SCH of the nature of a stencil plate is provided, which around its margin carries the characteristics of the associated subscribers in the form of definite stamping combinations. When at the end of the call the magnet D1 of selector WD1 is operated after the replacement of the receiver 60 at the calling station the disc SCH associated with the wipers a1 and b1 is advanced a step forward. As explained with reference to Fig. 1 the selector WD1 is only brought to rest when 65 the wiper a1 has reached the contact connected to wiper e of the calling subscriber. After wiper a1 has been set on wiper e of the preselector the disc is thus also brought to rest. It is then in such a position that the guide piece FS is arranged strictly in register with the stamping combination by which the calling subscriber is characterized. When the metering impulse train is transmitted the magnet SM receives the same 70 number of impulses as the transmitted metering impulses. The stamping pin ST1 is accordingly

pressed against the disc SCH a corresponding number of times. The stamping combination determined by the disc is thereupon indicated on the paper strip PS as many times as there are impulses in the metering impulse train. After 5 each stamping the paper strip is advanced. The corresponding advancing magnet is not shown in Fig. 2.

As was described in connection with the arrangement according to Fig. 1 only one impulse 10 is transmitted in the case of local calls and a plurality of metering impulses are transmitted only in the case of expensive calls, i. e., zone calls. It was also described that the zone magnet was only operated on the second metering impulse. 15 The zone magnet ZO possesses two special stamping pins ST2, of which one is displaced behind the other by a distance equal to the distance by which the strip is advanced each time. In the case of local calls the stamping combination 20 characterizing the calling subscriber is stamped on the paper strip only once without an additional indication being stamped by the magnet ZO. If, however, in the case of a more highly rated call several metering impulses are transmitted the stamping combination characterizing the calling subscriber is impressed on the first metering impulse and the paper strip is at the same time advanced one step forward. On the second metering impulse the same stamping 25 combination is again impressed upon the paper strip, and in addition the two stamping pins ST2 are operated by the zone magnet ZO so that both the stamping combination just impressed and also that previously impressed are provided with 30 the zone characteristic. On the next metering impulse the stamping combination characterizing the called subscriber is again impressed and simultaneously the zone characteristic. The stamping pin ST2 which is displaced one step 35 backwards now falls into the previously punched aperture so that after the second metering impulse only one zone characterizing stamping is impressed on the paper strip.

If the paper strip PS indicated in plan in the 40 lower part of Fig. 2 is considered it may be seen that the connection a was set up by a subscriber having the characteristic 1, 2, 4, 5, 6, and that this call was a zone call for which three metering impulses had to be taken into account. The 45 calls b, c, d, were local calls set up by subscribers with the characteristics 3, 5, and 2, 4, 5, and 5, 6.

What is claimed is:

1. In a measured service telephone system, 55 lines, a registering device, designations in said device corresponding to each of said lines, call charging means for transmitting one or more unit charges to said device in accordance with the value of a completed connection including a calling one of said lines, and means for recording 60 the designations of said calling line once for each unit charge transmitted to said device.

2. In a measured service telephone system, 65 lines, a registering device having designations for each of said lines, means for operating said registering device to select the designations corresponding to a calling one of said lines, call charging means for transmitting one or more unit charges to said device in accordance with the value of a completed connection including a calling 70 one of said lines, and means for recording the designations of said calling line once for each unit charge transmitted to said device.

3. In a measured service telephone system, 75 lines, a registering device having designations

- corresponding to each of said lines, means for completing a connection including a calling one of said lines, a selector switch associated with said device automatically selecting the calling line 5 when said connection is characterized as being chargeable, means responsive to the selective operation of said selector switch for operating said device to select the designations corresponding to the calling line, call charging means for transmitting one or more unit charges to said device in accordance with the value of the completed connection, and means for recording the designations of said calling line once for each unit charge transmitted to said device.
15. 4. In a measured service telephone system as claimed in claim 2 including means for controlling the selecting operation of said device prior to the unit charge transmitting operations of said charging means.
20. 5. In a measured service telephone system as claimed in claim 2 including means operative in response to the receipt of a release signal initiated by the calling line for controlling the selecting operation of said device.
25. 6. In a measured service telephone system as claimed in claim 2 including means operative in response to the selective operation of said device for transmitting an impulse to said charging means to initiate the transmitting operation of said charging means.
30. 7. In a measured service telephone system as claimed in claim 2 including means controlled by said charging means for maintaining said registering device in its selected position.
35. 8. In a measured service telephone system as claimed in claim 1 including means in said registering device operative in case higher value connections are completed, and additional designations recorded by said device in response to the 40 operation of said last means.
9. In a measured service telephone system as claimed in claim 1 including a switching device in said registering device corresponding to higher value connections, means for operating said switching device only in case a plurality of unit charges are transmitted by said charging means, and means controlled by said switching device for recording designations indicating high value connections.
45. 10. In a measured service telephone system as claimed in claim 1 including a switching device in said registering device corresponding to higher value connections, means for operating said switching device only in response to the receipt 50 of the second and all subsequent unit charges transmitted by said charging means, and means controlled by said switching device for recording designations indicating high value connections.
55. 11. In a measured service telephone system as claimed in claim 1, including a recording strip on which said designations are recorded, and means for advancing said strip in response to each recording operation.
60. 12. In a measured service telephone system as claimed in claim 1, including a switching device in said registering device corresponding to higher value connections, means for operating said switching device only in case a plurality of unit charges are transmitted by said charging means, and means controlled by said switching device for recording designations indicating high value connections, a recording strip on which the calling
- line and high value connection designations are recorded, and means for advancing said strip in response to each recording of the calling line.
13. In a measured service telephone system, a plurality of lines, a plurality of registering devices common to said lines, designations in said devices corresponding to each of said lines, means for operating any one of said devices to select the designations corresponding to a calling one of said lines, call charging means for transmitting one or more unit charges to said device in accordance with the value of a completed connection including the calling line, and means for recording the designations of said calling line once for each unit charge transmitted to said device.
14. In a measured service telephone system, lines, a registering device, designations in said device corresponding to each of said lines, call charging means for transmitting one or more unit charges to said device in accordance with the value of a completed connection including a calling one of said lines when the release of said connection is initiated, and means for recording the designations of said calling line once for each unit charge transmitted to said device.
15. In a measured service telephone system, lines, a registering device having designations for each of said lines, means for operating said registering device to select the designations corresponding to a calling one of said lines, call charging means for transmitting one or more unit charges to said device in accordance with the value of a completed connection including a calling one of said lines when the release of said connection is initiated, and means for recording the designations of said calling line once for each unit charge transmitted to said device.
16. In a measured service telephone system, lines, a registering device having designations corresponding to each of said lines, means for completing a connection including a calling one of said lines, a selector switch associated with said device automatically selecting the calling line when said connection is characterized as being chargeable, means responsive to the selective operation of said selector switch for operating said device to select the designations corresponding to the calling line, call charging means for transmitting one or more unit charges to said device in accordance with the value of the completed connection when the release of said connection is initiated, and means for recording the designations of said calling line once for each unit charge transmitted to said device.
17. In a measured service telephone system, a plurality of lines, a plurality of registering devices common to said lines, designations in said devices corresponding to each of said lines, means for operating any one of said devices to select the designations corresponding to a calling one of said lines, call charging means for transmitting one or more unit charges to said device in accordance with the value of a completed connection including the calling line when the release of said connection is initiated, and means for recording the designations of said calling line once for each unit charge transmitted to said device.
